UNITED STATES PATENT OFFICE.

ALFRED INGRAM AND HARRY INGRAM, OF BROOKLYN, NEW YORK.

CLOSURE FOR BOTTLES, JARS, AND OTHER RECEPTACLES.

1,292,473.

Specification of Letters Patent. Patented Jan. 28, 1919.

Application filed September 6, 1916. Serial No. 118,611.

To all whom it may concern:

Be it known that we, ALFRED INGRAM and HARRY INGRAM, citizens of the United States, and residents of Brooklyn, in the county of Kings and State of New York, have invented certain new and useful Improvements in Closures for Bottles, Jars, and other Receptacles, of which the following is a specification.

10 The invention pertains more particularly to crown caps and to means carried thereby for permitting the convenient removal of the cap from a bottle. As is well known, crown caps have a top or crown portion, a 15 depending skirt portion to be crimped over a shoulder on the outside of the neck of the bottle and a cork or other sealing disk located within the crown portion to engage the upper edges of the bottle. Usually these 20 crown caps are removed from bottles by independent appliances commonly called cap lifters. The disadvantages of independent cap lifters for removing the caps have been recognized and various attempts have been 25 made to remedy the same and some of these have involved the connection of devices with the cap, for removing it from a bottle, but these means, so far as we are informed, have been vitally defective in at least two important particulars, one being that their 30 construction and application to or connection with the caps have generally rendered it impossible to handle the caps in the hoppers of commercial capping machines, and the 35 other being the greatly increased expense attending the production of the cap caused by the devices referred to, some of which have been integral with the caps and thus very greatly increased the expense of producing 40 the cap due to the great waste of metal in cutting the cap and its appendage in a single piece from sheet metal.

The purpose of our invention is to provide a crown cap with simple and inexpensive 45 means conveniently applied thereto for permitting the removal of the cap from a bottle said means preferably consisting of a ring or band adapted to embrace or extend around the edges of the crown of the cap 50 and made from a strip whose ends are inserted through a hole in the upper side edge of the cap and bent laterally so as to lie between the sealing disk and the inner side surface of the cap. The ring or band is

preferably made from a flat strip of metal, 55 and, when in normal position on the cap, will be disposed on edge, or in other words stand vertically close against and embrace the upper side portions of the cap. When it is desired to remove the cap from a bottle, 60 the ring or band will be turned upwardly at its free edge in position to receive any convenient device, such as a knife handle, lead pencil, or the like, whereby through a pull on said ring or band the cap may be 65 detached from the bottle.

The cap and removing ring or band embracing our invention may be as conveniently handled in hoppers of commercial capping machines as the ordinary crown 70 caps possessing no means for their removal, and in addition the means we provide for detaching the cap adds very slightly to the expense of manufacturing the cap and in no way interferes with the proper sealing of the 75 bottle.

Our invention further affords certain specific advantages in that the ring or band may be made of very thin metal and present a flat surface to the device which may be inserted through it when a cap is to be removed, and further, when the ring or band is turned upwardly and force applied for detaching the cap, the strain on the metal of the ring or band at the point of its connection with the cap is in line with the vertical diameter of the metal, this diameter and the direction of the strain on the metal serving to permit the successful use of a very thin band or ring as a cap lifting attachment. 85

The invention will be fully understood from the detailed description hereinafter presented, reference being had to the accompanying drawings, in which: 95

Figure 1 is a top view, partly broken away and partly in section, of a cap embodying our invention, the lifter applied thereto being shown closed down around the crown of the cap in normal inoperative 100 position;

Fig. 2 is a bottom view, with the sealing disk partly broken away, of the same;

Fig. 3 is a central vertical section through the neck portion of a bottle having the cap 105 of our invention applied thereto, and

Fig. 4 is a like view of the same with the lifter ring or band shown as turned up-

wardly preparatory to being used for detaching the cap from the bottle.

In the drawings, 10 indicates the neck portion of a bottle of usual construction, 5 11 an annular groove in the exterior of the upper end portion of said neck, 12 the contents of the bottle, and 13 a cap applied upon the mouth of the bottle and comprising a top or crown portion 14, a corrugated 10 skirt portion 15 adapted to be crimped into the aforesaid groove, as usual, a side portion 16 intermediate the top 14 and skirt 15, and an inner disk 17 of cork or other sealing medium, as usual; and the cap 13 apart 15 from the features of our invention is of customary form and construction and adapted to be applied to the mouths of bottles in the usual manner, the sealing zone which we will number 18 being annular and 20 disposed inwardly from the side 16 surrounding the top of the cap.

Our invention resides more particularly in special means provided by us for enabling the removal of the cap from the bottle without 25 the employment of an independent cap lifter, many types of which are well known. In accordance with our invention we do not modify the construction of the cap 13 further than to form at one point in the 30 side 16 thereof a vertical slit or opening 19, and in carrying out our invention we equip the cap with a ring loop or band 20 preferably formed from a flat strip of steel or other metal having its ends inserted through 35 the opening 19 and then bent laterally in opposite directions, as at 21, 22, said ends being against the inner surface of the side 16 and between said surface and the outer vertical edge of the sealing disk 17, 40 and thus being outwardly beyond the sealing zone of the cap and above the inwardly crimped skirt portion 15 of said cap. Initially the ring or band 20 and its laterally bent ends 21, 22 are vertical, with the body 45 of the ring or band 20 closely encompassing the side 16 of the cap directly below the top 14, as shown in Fig. 3, wherein it may be seen that the ring or band 20 and its ends 22 are all on vertical planes or arranged on edge, the longer diameter of the 50 material of the ring or band and its parts being vertical. The ring or band 20 by being formed from a strip of thin flat metal and disposed with relation to the cap in 55 the manner indicated, that is below the top 14 and above the crimped skirt portion 15, occupies very little space and its disposition is such that the cap may be conveniently handled in the hoppers of ordinary commercial capping machines, without which 60 characteristic the cap as a whole would be rendered impracticable for general commercial use. The ring or band 20 is inexpensive to manufacture and obviously it may 65 be applied to the cap with great conven-

ience and such expedition as not to materially increase the cost of the manufacture of the cap. The laterally bent ends 21, 22 of the strip constituting the ring or band 20, efficiently secure the ring or band and being flat and held between two flat surfaces prevent the accidental turning upwardly of the free edge of the ring at the side of the cap opposite to the opening 19. The arms 21, 22 by being exterior to the sealing zone 70 18 and between the edge of the disk 17 and the adjacent inner side surface of the cap, do not interfere with the sealing of the bottle and, in addition, are protected against contact with the contents of the bottle. 80

When it is desired to remove the cap from or open a bottle, the free edge of the ring or band 20 will be turned upwardly or to about the position shown in Fig. 4, and thereupon a knife handle, lead pencil or 85 other convenient instrument may be inserted through the ring or band 20 and used as a handle for pulling upwardly on said ring or band in a direction to detach the cap from the bottle. We have found that by a proper application of the forefinger in the ring or band 20 and the thumb to the bottle, the finger may be employed for pulling on the band 20 and thereby detaching the cap from the bottle, but ordinarily 90 it will be found more convenient and possibly more agreeable to insert a lead pencil or other device through the ring or loop 20 to serve as a handle for detaching the cap. When the ring, loop or band 20 is 95 turned upwardly and a pull is exerted thereon for detaching the cap, the strain of the pulling force is against the vertical diameter of those portions of the ring or band adjacent to the opening 19, as shown in 100 Fig. 4, and this detail of the structure is important in that it permits the use of very thin metal in the ring or band without impairing the efficiency of the same as a cap remover or lifter. The ends of the band 20 105 are contiguous to each other, and this is another detail of the structure which is important, in that thereby when the band is in use, the pull is at substantially a single point at one edge of the cap and that the 110 cap may be detached from the bottle with limited strain on the hand of the person detaching the same. The manufacture of the ring or band 20 from a strip of flat metal results in the band presenting a flat 115 surface not only to the side of the cap, but also to the finger or to such instrument as may be inserted through the same to be used in applying the force for detaching the cap. We regard the use of a substantially flat strip in making the ring or band 20 as highly important, but we do not desire to limit our invention in every instance to the employment of a flat ribbon or strip for the manufacture of the ring or band 20. 120

What we claim as our invention and desire to secure by Letters Patent, is:

A closure for bottles and other receptacles comprising a cap containing a sealing medium and having a depending side portion, and means carried by the cap for detaching the same, said means being a band closely encircling the upper side portion of the cap and free at one side to be turned upwardly and afford an open loop and at the other side at a given point being fastened to said

cap, so that an upward pull on the loop will be directed at a predetermined point against one edge only of the cap.

Signed at New York in the county of 15
New York and State of New York this 5th
day of September, A. D. 1916.
